NECKTIE

Lee Roy Sanders, Oklahoma City, Okla.

Application September 14, 1951, Serial No. 16,636

Term of patent 3½ years

(Cl. D3—16)

To all whom it may concern:

Be it known that I, Lee Roy Sanders, a citizen of the United States and resident of Oklahoma City, county of Oklahoma, State of Oklahoma, have invented a new, original, and ornamental Design for a Necktie, of which the following is a specification, reference being had to the accompanying drawing, forming a part thereof.

The figure on the drawing is a perspective view of a necktie showing my new design.

The ornamentation is confined to the area within the heavy-line portions, the remainder of the necktie being conventional and unornamented.

I claim:

The ornamental design for a necktie, substantially as shown and described.

LEE R. SANDERS.
